Primary Examiner — Selina Sikder(74) *Attorney, Agent, or Firm* — Saidman DesignLaw
Group, LLC(57) **CLAIM**We claim the ornamental design for a control device, as
shown and described.

DESCRIPTION

FIG. 1 is a perspective view of a control device showing our
new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view showing an alternate environment.

FIG. 8 is a front view thereof.

FIG. 9 is a left side view thereof.

FIG. 10 is a right side view thereof.

FIG. 11 is a top view thereof; and,

FIG. 12 is a bottom view thereof.

The rear views form no part of the design and are omitted.
The portions of the drawings appearing in broken lines are
for environment only and do not form part of the claimed
design.**1 Claim, 8 Drawing Sheets**| (56)	References Cited
